UNITED STATES PATENT OFFICE.

BERNHARD FRITZSCH, OF CINCINNATI, OHIO.

LEATHEROID AND PROCESS OF MAKING THE SAME.

1,334,297.

Specification of Letters Patent. Patented Mar. 23, 1920.

No Drawing.

Application filed November 7, 1918. Serial No. 261,463.

To all whom it may concern:

Be it known that I, BERNHARD FRITZSCH, a citizen of the United States, and residing at Cincinnati, in the county of Hamilton and State of Ohio, have invented a new and useful Improvement in Leatheroid and Processes of Making the Same, of which the following specification is a full disclosure.

My invention relates to a new leatheroid and the process of making the same.

The objects of the invention are to produce a leatheroid from cheap and abundant materials by a simple process.

Another object of the invention is to produce a substantially water-proof leatheroid.

My product is a uniform grade of commercial leatheroid, having useful properties and physical characteristics available for many uses, and as a leather substitute for some purposes.

My invention rests on the discovery that leather, rubber, casein and lime can be inter-incorporated into a homogeneous, bonded mass, which, dough-like, can be rolled into sheets of any desired thickness, which when dry and solidified has desirable texture, physical structure and qualifications. While these four materials form the basis of my product, it is obvious that to produce slight gradations of products, other materials, such as sulfur, or wood or cotton pulp, can be added, without departing from the said four basic components, as the underlying principle of the invention. That is to say, my mixture constitutes a leather-like base, to which slightly varying characteristics can be imparted by slight additions of other materials, the contributing characteristics of which are well known to the art.

For the leather component, I use, preferably, cheap waste material, such as old leather, tannery scraps, shoe or harness trimmings and the like, which are abundant and cheap, and which are largely waste or by-products at present.

For the rubber component, I preferably use the best commercial (washed) rubber or para dissolved in naphtha, or other suitable volatile material.

The casein is ordinary cheese, such as dry cottage cheese, and constitutes a bonding and water-proof material.

I preferably use ordinary unslaked lime, but barium or aluminum oxid, or an alkaline earth metal oxid can be employed to provide this component, which adds strength, water-proof characteristics and density to the product.

To exemplify the process, and without limiting the invention to definite proportions, I have obtained the best results by using five parts leather, five parts rubber, one part casein and one-third part of unslaked lime or its equivalent. The leather is ground up very fine, the rubber is dissolved, and the four materials are thoroughly mixed while cold, until the several ingredients are thoroughly blended and inter-incorporated into a substantially homogeneous mass, which is pliable, non-tenacious and moist, and can be likened to a dough or fudge-like body, which can be rolled or pressed, when about half dry, into sheet formation, without disruption of the unitary mass. This body is rolled or pressed into sheet or block formation and allowed to stand and dry and harden into a distinct body of useful leatheroid structure, property and physical characteristics. It can also be molded into articles, being admirably adapted for tire casings. That is, it is soft, pliable, has a leatheroid grain, resists ruptural strains and is water-proof. Leather surface finishes and stains can be readily imparted to it and it can be worked up into many desired leather substitute products.

The mass when still wet and pliable can be pressed upon a linen or fabric base, adhering thereto and forming a leatheroid faced fabric, suitable for furniture covering or automobile tops.

As illustrating the nature of this new material, specimens are filed herewith.

While the product is, in a sense, a leather compound, it constitutes in reality a leatheroid, and is a uniform, unitary homogeneous material, the properties, appearance, and usages of which, render it available for a wide variety of uses, other than a mere leather substitute.

This material is not readily combustible and is also suitable for insulation.

By this process and with these materials, the leather and rubber particles are closely

and tenaciously bonded together, producing a relatively stout tissue of uniformly firm coherence.

I claim:

- 5 1. A leatheroid comprising an admixture of leather, rubber, casein and an alkali earth metal oxid.
2. A leatheroid comprising an admixture of leather, rubber, casein and lime.
- 10 3. A leatheroid comprising a mixture of about equal parts of leather and rubber, a small portion of casein, and a still smaller portion of a metallic base.
4. A leatheroid comprising an admixture 15 of approximately five parts leather, five parts rubber, one part casein and a small portion of an alkali earth metal oxid.

5. The herein disclosed process of making leatheroid, which consists in admixing leather and rubber particles, casein and an 20 alkaline earth metal oxid.

6. The process of making leatheroid, comprising admixing in wet state, leather and rubber particles in about equal proportion, a small part of casein, and a still smaller 25 part of an alkaline earth metal oxid.

In witness whereof, I hereunto subscribe my name, as attested by the two subscribing witnesses.

BERNHARD FRITZSCH.

Witnesses:
